APPARATUS FOR DRYING EXCAVATIONS

John T. Cullen, Hayward, Calif., assignor to
 Pacific Pumping Company, Oakland, Calif., a
 corporation of California

Application June 10, 1950, Serial No. 167,439

4 Claims. (Cl. 166—1)

1

This invention relates to an apparatus for keeping seepage water exhausted from excavations or ground areas which are lower than the generally prevailing water level.

The invention has particular application to construction projects, such as tunnels, sewers, bridge pier foundations, etc. When a tunnel is to be built in a ditch or a bore, the contractor is often plagued by water which seeps into the ditch or bore from one source or another and makes it impossible to do the work unless the water can be kept out during the construction period.

For many years, this water has been controlled somewhat by a method employing a plurality of well points connected to a header which in turn is connected to one or more high-vacuum pumps.

The method of the present invention achieves a distinct advance over the old method and solves problems which have interfered with the efficiency and the satisfactory use of the old method.

One of the problems solved is that with the new method when the area around a well point goes dry, so to speak, and air is sucked into the line through the well point, there is no interference with the efficiency or working of the other well points in the system. With the old suction pump and header method, when one or more well points went dry, the minus pressure (suction) of all the other well points would drop and so would diminish their ability to pick up water and carry it up to the pump. Different plans have been tried in the past with the old method to shut off a particular well point suction line as soon as the operator became aware that its well point was sucking air. In the first place this has meant an operator in constant attendance on the system and he has tried by watching glass tubes set in the suction line or by ear to detect which well point lines should be shut off. The present method eliminates the need for an operator in constant attendance and provides a fool-proof, automatic dewatering system. This is not only an economy to all concerned, but the increased efficiency of the new system keeps holes dry which before never could be kept perfectly dry.

In describing the method, a suitable apparatus has been shown in the drawings, in which:

Fig. 1 is a schematic view in perspective showing the system as applied to a ditch;

Fig. 2 is a detail view in elevation, partly in section, showing a form of individual jet pump and a form of well point; and

Fig. 3 is a like view of a form of air release.

In using these forms of devices to illustrate the application of my method and apparatus, I do not intend thereby to limit it, except as is required by the appended claims.

The apparatus shown in Fig. 1 includes a cen-

2

trifugal pump 10 (normally classified as a vertically-split case or a horizontally split-case) driven by any suitable available power source 11. In this case it is an electric motor. The inlet 12 of the pump 10 is connected by a pipe to an air separation chamber and reservoir 14 for starting the system after a shutdown. The outlet 15 of the pump 10 is connected to what I call a high pressure header 16 from which the leads 17, 17, 17, 17 run to the individual jets 18 (see Fig. 2), each of which is positioned above and connected to the outlet of a well point 19. Shut off valves 20 in each lead 17 facilitate selection of the well points to put in service.

The well point 19 (see Fig. 2) includes a pipe 21 having an opening or series of openings 22, surrounded by a fine screen 23 with a heavier protecting screen 23a around the whole. The outlet 24 of the well point is connected to the chamber 25 in the jet housing 26 by the pipe 27. This chamber surrounds the jet nozzle 18 and opens into the jet venturi 28, so that when the water or other liquid being pumped through the header 16 rushes from the nozzle 18 it creates a vacuum in the Venturi tube 28, thus lowering the pressure in the well point 19 and causing the water 29 around the well point to flow in through the screens, up into the Venturi chamber 25 and into the Venturi tube 28. There it mixes with the water from the nozzle 18, and the total of nozzle capacity and flow through the well point passes on up through the pipe 30 into the return or low pressure header 31 and into the reservoir 14.

On the return header 31, at its highest point where air will collect, I prefer to put an automatic air vent valve 32, having a float 33 on an arm 34 which opens and closes the valve disc 35 on the outlet orifice 36 (see Fig. 3).

So long as water fills the system, the float remains buoyed up and holds the valve disc to its seat. As air accumulates, it displaces the water in the body of the valve and the float falls as the water recedes, thus pulling the disc off its seat. The accumulated air is then discharged by the pressure in the system. As the water rises in the body, the float returns the disc to its seat, and prevents water from escaping. When air collects again, the cycle is repeated. On a header 31 which is 400 feet long there may be several of these air vent valves 32.

On each return line 30 is a valve 37 to be closed whenever the valve 20 on the pressure line 17 is closed. This would be at a time when any particular well point was to be inactivated.

In an installation each set of branch leads 17 and 30 are usually about 5 feet apart from the next set, but this distance may be varied to suit the volume of water that has to be withdrawn from the excavation.

The water picked up through the well points 19 represents a surplus over that being pumped down the line 17, and will flow out the overflow of the tank 14, leaving in the tank all the liquid needed to keep the system primed and the header 16 and pipes 17 filled. The overflow is placed at a point higher than the inlet of the pump 10.

I have found that the system works well with a pressure of 55 to 70 pounds in the high pressure header 16 and with a pressure of 0 to 15 pounds in the return or low pressure header 31.

The centrifugal pump 10 has to be big enough to supply the demand of the combined capacities of the jet nozzles 18. Any number of these nozzles may be used so long as the pump 10 has the required output.

My new system of dewatering is accomplished by the use of a plurality of jets 18 connected as herein set forth so that if one or more well points 19 have exceeded the flow of water into them through the openings 22 and are taking in air, this will in no way affect or decrease the efficiency of the other well points which are still submerged in water. It was this discovery of this new method which solved the old problem, inherent in vacuum pumping, namely, that when one or more well points began sucking in air, the vacuum in the whole system decreased and therefore the amount of water sucked up through the well points still submerged in water dropped off. This meant that in the old method it was necessary to exercise constant vigilance over the well points so that those that were dry, for the moment, could be cut out of the system by a valve. Glass tubes for sighting to detect when a well point went dry, and listening to determine if air or water was flowing from any particular well point, as well as other means were tried in the old method without success.

By the new system described herein it is now possible to cut down on the labor force necessary to keep the system operating, and it is even possible on a job to go away and leave it operating unattended over the week-end and for long periods of time. This was unheard of with the old system.

Another very distinct advantage of this new method is that it can be used in an excavation of any depth simply by running the leads 17 from the high pressure header 16 (usually at the surface level) and the leads 30 from the return header 31 (usually also at the surface level) down into the excavation no matter what its depth, while the pump 10 and the reservoir 14 are kept up on the working level where they are easy to watch and to repair. With the old system of using mechanical pumps to lift the water, the 15 to 20 foot lift possible with vacuum made it necessary in any excavation of over 15 to 20 feet to put another complete well point system at the 15 or 20 foot level. This system operated entirely independently of the system at the higher level. This is called staging and there had to be as many independent systems, one at each stage, as there were multiples of 20 feet in the depth of the excavation.

This indicates too that in deep excavations under the old method of staging, the cost of equipment goes up as each additional independent unit is required on each stage.

My improved system also dispenses with the vacuum pump which was needed on the old system.

The net effect of this new system is that it keeps the water level down below grade, drying

up the sub-grade so the contractor is working in the dry. It does this with an individual jet installed at each well point. No matter whether one or twenty well points are sucking part air with the water, or even all air, this does not affect the performance of the system.

No matter whether the excavation is twenty or forty feet deep, the supply pipes can still be on the ground surface, with just the individual lines going down to the well points, because the actual pumping is done right above the point with the jet. This keeps the piping out of the way; completed sections can have the points removed and the excavation backfilled, with the points moved ahead for further excavation, without disturbing the supply pipes.

I claim:

1. In a continuous automatic dewatering system for evacuating water or other fluids which 20 come into an excavation or into the ground adjacent to it, the combination of a plurality of well points set in the ground adjacent said excavation, each with its inlet opening at about the level at which it is desired to hold any seepage, a jet pump including a venturi in communication with each well point, said pump having its inlet connected to the outlet of its associated well point, a fluid pressure feed manifold, a continuous fluid pumping means, having its 30 outlet connected to said fluid pressure feed manifold; means connecting the intake conduit of the jet of each jet pump to said pressure feed manifold; a fluid return line connected to said continuous fluid pumping means; and means connecting the outlet of the venturi of each jet pump to said return line, whereby each jet pump will pick up any water which enters its associated well point and will project it into said fluid return line and air which may be picked up by 40 any one or more of said jet pumps will not reduce the efficiency of the jet pumps having water in their respective well points.

2. The device of claim 1 together with a float controlled air release means in the fluid return line.

3. The device of claim 1 together with a reservoir connected to said fluid return line, and said reservoir having an overflow outlet above the level of the inlet to said continuous fluid pumping means.

4. The device of claim 3 in which said continuous fluid pumping means, and said fluid pressure feed manifold are disposed at or near the ground level alongside said excavation.
